United States Patent Office

Des. 188,615
Patented Aug. 16, 1960

188,615

COMBINED WARMING DISH AND STAND THEREFOR

Victor J. Bergeron, Orinda, Calif.
(20 Cosmo Place, San Francisco, Calif.)

Filed Mar. 28, 1960, Ser. No. 59,893

Term of patent 14 years

(Cl. D44—15)

FIG. 1

FIG. 2

I claim:

The ornamental design for a combined warming dish and stand therefor, as shown.
